UNITED STATES PATENT OFFICE

2,595,094

CANOPY AWNING

John B. Niles, Los Angeles, Calif.

Application August 30, 1948, Serial No. 46,757

1 Claim. (Cl. 211—180)

1

This invention relates to canopy awnings and the primary object of the invention is to provide a canopy awning adapted to be supported in folded and in extended position on clothes lines attached to cross arms secured to oppositely arranged posts similar to clothes line supporting means of the kind described and shown in the copending patent application Serial No. 794,284, which has matured into Patent No. 2,576,805 of November 27, 1951.

A further object of the invention is to provide a canopy awning of the character indicated above, wherein the awning material is equipped adjacent each of its ends with a stiffening member extending transversely of said material and adapted to be releasably secured by any conventional means to the cross arms on the clothes line poles.

Another object of the invention is to provide a canopy awning of the character indicated above, wherein the awning material is provided adjacent to each of its longitudinal edges with a plurality of spring rings or the like adapted to be snapped onto the outside clothes lines supported by the cross arms secured to the clothes line posts, so that the awning material is attached slidably and removably to said clothes lines.

An additional object of the invention is to provide a canopy awning of the character indicated above, the intermediate portion of which is supported by the intermediate clothes lines secured to the cross arms on the clothes line posts, so that said awning portion is prevented from sagging and that the clothes lines, when not in use for the purpose of supporting clothes, are protected against being soiled by soot or the like.

Other objects of the invention not specifically mentioned may appear in the following specification describing the invention with reference to the accompanying drawings illustrating a preferred embodiment of the invention, which resides in the details of construction and the combination and arrangement of parts as hereinafter more fully set forth. It is, however, to be understood, that the invention is not to be limited or restricted to the exact construction and combination of parts described in the specification and shown in the drawings, but that such changes and modifications can be made, which fall within the scope of the claim appended hereto.

In the several figures of the drawings similar parts are indicated by similar reference characters and wherein:

Figure 1 is a view in top plan of a canopy

2

awning constructed in accordance with the present invention.

Figure 2 is a detail section on an enlarged scale taken substantially on the line 2—2 of Figure 1.

5 The canopy awning herein embodied comprises a pair of spaced apart, oppositely arranged supports S, preferably similar to the clothes line post shown and described in the copending patent application Serial No. 794,284.

10 Each support S consists substantially of an upright post 10 supporting a cross arm 11. A plurality of flexible elements 12, such as clothes lines or the like, are secured to the oppositely arranged cross arms by means of spring biased hook rods 13 extending diametrically through said cross arms whereby the clothes lines 12 are held taut between the two cross arms.

A canopy awning body 14 is made from an elongated rectangular piece of awning cloth 15.

20 Adjacent to each cross edge of said cloth piece and at suitable intervals between said edges stiffening members 16 are attached to the awning body and are made from any suitable conventional material such as a piece of tubing or the like.

25 The stiffening members 16 may be secured to the awning member 14 in any conventional manner, but preferably a transversely extending pocket 17 is formed in the body 14 and at suitable intervals between said edges and in each of

30 these pockets 17 one of the stiffening members 16 is inserted. The awning body 14 is arranged over the clothes lines 12 and its end portions are removably secured to the cross arms 11 by means of light ropes 18 or the like. Secured to the

35 under side of the awning body 14 are longitudinal rows of equidistantly spaced spring rings 19, one row for each of said flexible elements 12, which are adapted to be snapped onto the latter so that they are slidably and removably mounted thereon.

40 In this manner the awning body 14 is secured onto the supports S so that it is adapted to be extended over the area between the two supports to provide a shaded shelter in the patio, yard, etc., in which the supports S are permanently mounted, and that it is adapted to be slidably moved toward one of the supports to be secured there in accordion-like gathered position, so that the clothes lines 12 can be used for the purpose of supporting clothes.

45 50 I claim:

In a canopy awning, a pair of spaced uprights, cross bars supported at their centers by said uprights, a plurality of eyebolts passed through said cross bars in equidistantly spaced relation along the length thereof, a flexible element

stretched taut between said cross bars and secured to each aligned pairs of said eyebolts, an awning supported on said flexible elements, tie elements secured to the lower side of the opposite ends of said awning to fasten the same to said cross bars, ring elements carried by the under side of said awning and engaged with said flexible elements whereby the awning may be slid end-wise along the same toward one of said cross bars, upon the release of said securing means of 10 the awning from the other of the cross bars, to expose the flexible elements for use as clothes lines, spaced pockets formed transversely on the lower side of the awning, and a rod housed within each of said pockets to maintain the awning taut crosswise of said flexible elements.

JOHN B. NILES.
